UNITED STATES PATENT OFFICE.

REUBEN HITCHCOCK, OF CLEVELAND, OHIO, ASSIGNOR TO THE CLEVELAND FOLDING MACHINE COMPANY, OF CLEVELAND, OHIO, A CORPORATION OF OHIO.

SHEET-DELIVERY TABLE.

Application filed July 2, 1923. Serial No. 649,100.

To all whom it may concern:

Be it known that I, REUBEN HITCHCOCK, a citizen of the United States, residing at Cleveland, in the county of Cuyahoga and 5 State of Ohio, have invented certain new and useful Improvements in Sheet-Delivery Tables, of which the following is a specification.

My invention relates to improvements in 10 sheet delivery tables and has for its object the provision of means for driving the diagonally positioned rolls thereof more effectively than is obtainable with driving mechanism in use at the present time.

15 A difficulty commonly encountered with the driving mechanism of the prior art has resided in the displacement of the under-running belt commonly employed for this purpose. With the diagonally positioned 20 rolls of different lengths, which are used in sheet delivery tables, there is a recognized tendency of the belt, which also must drive in a diagonal position, but at right angles with the rolls, to slip out of proper position 25 with respect to its driving pulley and thereby seriously wear the edges of the belt. This tendency has been attributed to the difficulty of maintaining accurately aligned 30 bearings for the rollers and, possibly, the different drag which these rollers of different lengths impart to the belt.

Accordingly, it has been my purpose to 35 produce a driving mechanism which shall avoid the difficulty above referred to and improve the efficiency of the drive. For this purpose I have associated with the driving belt and its adjacent mechanism suitably co-acting paired rollers which shall engage the belt closely adjacent to its driving pulley 40 and beyond the tightening device or adjustment, whereby said belt is caused to ride into its proper position upon the pulley. Further features of construction and operation may best be explained by making reference to the accompanying drawings wherein:

Fig. 1 is a plan view, partially broken away, of a sheet delivery table;

50 Fig. 2 is a similar detached view of the driving mechanism therefor embodying my invention;

Fig. 3 is a longitudinal sectional view thereof, partially diagrammatic in character;

55 Fig. 4 is an enlarged transverse view of

the guiding rolls for the belt, on line 4—4, Fig. 2;

Fig. 5 is an enlarged longitudinal section 60 of a modified belt drive embodying my improvements;

Fig. 6 is a transverse view, on line 6—6, Fig. 5; and

Fig. 7 is a longitudinal sectional view of another type of modified belt guide.

Throughout the several figures of the 65 drawings I have employed the same character of reference to indicate similar parts.

Referring first to Fig. 1, the essentials of the well-known type of delivery table are shown, comprising the diagonally positioned 70 rolls *a* of varying length journaled within the irregular supporting frame *a'*. These rolls are driven by a diagonally extending belt *b* under-running said rolls and pressed against the same by flanged idlers *c* normally interposed between each pair of rolls, as best shown in Fig. 3. The driving pulley *d* is actuated by the bevel gears *e e'* positioned at one corner of the frame. It will be understood that the lower length of the belt *b* is 75 travelling from left to right, and pivoted adjustment *f*, controllable by the screw mechanism *g*, is disposed approximately midway of its length, for tightening the belt as required. Beyond this adjustment, and 80 closely adjacent to the driving pulley *d*, there are positioned two grooved idlers *i*, best 85 shown in Figs. 2 and 4, between which the belt loosely runs; but said idlers are properly spaced so that they will center the belt 90 upon the driving pulley and thereby cause it to assume the proper position in its travel over the flanged idlers *c*, as best shown in Fig. 2.

With the belt properly adjusted by the 95 pivoted member *f* and its screw-acting means, all tendency of said belt to ride upon one or the other of the lateral sets of flanges upon the idlers *c* is effectively avoided, so that the stretching of one edge or the other 100 of the belt, and its wear or abrasion, are positively overcome.

The construction shown in Figs. 5 and 6 upon a somewhat larger scale embodies the 105 same principles; the adjustment being one that is adapted for use upon certain types of delivery table, whereby one may apply my present invention without further modification. In this particular construction the idlers *i* are mounted upon angularly extend- 110

ing arms i' , supported within the yoke j , bolted to the frame j' of the driving mechanism. Said idlers are shown positioned a little more closely to the driving pulley d than in the preceding figures.

Fig. 7 illustrates another slight modification wherein an ungrooved roller i'' is mounted near the end of the arm i' and serves the same purpose of positioning and guiding the edges of the driving belt, not shown in this figure.

It will be appreciated that with the spaced idlers or rollers i , interposed between the belt adjustment, and its driving pulley closely adjacent to the latter, that even with a relatively slack belt, which is desirable for flexing it into position against the under side of the rolls a , said belt will run true throughout its upper length despite the numerous flexures necessary to insure efficient driving of the rolls a . Moreover, certain improvement in efficiency is obtainable by employing the invention herein described, and longer service is insured for the driving belt than is obtainable without my improvement.

Having now described the apparatus embodying my invention, I claim as new, and desire to secure by Letters Patent, the following:

1. The combination with a plurality of parallel advancing rolls in a sheet delivery table, of driving mechanism therefor comprising an under-running belt, a driving pulley for the belt positioned at one end of the delivery table, adjusting means for said belt adapted to regulate its tension, and centering mechanism for the belt interposed between the adjusting means and the driving pulley, comprising an opposing pair of grooved pulley wheels spaced to align with the edges of the belt and positioned adjacent to the driving pulley, substantially as set forth.

2. The combination with a sheet delivery table comprising a plurality of parallel advancing rolls, driving mechanism therefor including an under-running belt engaging said rolls and its driving pulley, of an adjustable belt-centering appliance adapted to be positioned in advance of said pulley, including a supporting frame and two grooved pulley wheels in opposing relation spaced apart to engage the edges of said belt adjacent to said driving pulley, substantially as set forth.

In testimony whereof I do now affix my signature.

REUBEN HITCHCOCK.
